UNITED STATES PATENT OFFICE.

HARRY LANDSIEDEL, OF CINCINNATI, OHIO, ASSIGNOR TO THE DALTON ADDING MACHINE COMPANY, OF NORWOOD, CINCINNATI, OHIO, A CORPORATION OF OHIO.

DESIGNATING-COLUMN MECHANISM FOR ADDING MACHINES.

Application filed May 31, 1923. Serial No. 642,401.

This invention relates to means adapted for use in connection with adding machines of well known type whereby one of the type carrying racks or sectors may be used to 5 carry types for printing numeral characters such as fractions which are accumulated into the machine or designating characters which are not required to be accumulated and added and when used in the latter manner the 10 accumulating devices are omitted. The designating column mechanism is caused to function, when required, by manipulation of the keyboard which permits the desired designating stops to be set to control the ampli- 15 tude of movement of the designating column sector which is used in conjunction with the usual sectors and key controlled stops which function in a well known manner in the listing, accumulating and totaling of items. 20 The provision of the designating column mechanism in no way interferes with the regular functioning of the adding machine, and makes it possible to use the designating column for handling fractions which are ac- 25 cumulated and totalized in conjunction with the whole numbers which are added in the usual manner.

Other objects will appear from a detailed description of the invention, which consists 30 in the features of construction and combinations of parts hereinafter described and claimed.

In the drawings:

Figure 1 is a sectional elevation of the 35 well known Dalton adding machine showing the general relation of the various parts which constitute this invention;

Fig. 2 is a rear elevation of the same;

Fig. 3 is a plan view of the stop carriage 40 locking mechanism;

Fig. 4 is a rear elevation of the same;

Fig. 5 is a plan view of the designating column latch and release mechanism;

Fig. 6 is a front sectional elevation of the 45 stop carriage, key bar tappet and heels of the regular and designating racks in contact with the stops;

Fig. 7 is a plan view of the stop carriage locking mechanism with associated parts;

Fig. 8 is a side view, taken from the left 50 side of the machine as viewed from the front, showing the designating column latch and the subtraction release member; and

Fig. 9 is a side view from the same side 55 of the machine showing the total release

member for releasing a designating column latch.

No attempt will be made to describe the construction and mode of operation of the various parts of an adding machine to which 60 this device is applied, since the construction and mode of operation are well known to those skilled in the art being in general similar to those shown in Hopkins Patent No. 1,039,130. Only those portions of a stand- 65 ard machine will be specifically referred to which are intimately associated with the mechanism constituting the present invention.

Since the designating column mechanism 70 of the present invention can be used for the purpose of adding fractional units, and since, when so used, this mechanism must be intimately co-related to and harmonized with the standard mechanism for handling 75 whole numbers, the present description will be directed primarily to the use of the designating column mechanism for fractional purposes with the understanding, however, that the same mechanism, with certain parts 80 omitted, can be utilized for designating purposes only if such use is desired.

The machine as a whole comprises a cas- 85 ing 10, a traveling stop carriage 11, a platen 12, type carriers 13, associated racks 14, and adding wheels 15, which parts are associated with the necessary actuating mechanism in a manner fully understood by those skilled in the art.

As viewed from the front of the machine, 90 the designating column mechanism occupies the right hand position and the type sector with its associated rack and adding wheel, shown in Fig. 1, may be considered as the designating column train of mechanisms 95 designated to function in the listing, accumulat- 100 ing and totalizing of fractions or listing only of designating symbols. For purposes of illustration, it may be assumed that provision is made for fractions of one eighth or for the employment of eight designating symbols as the case may be, and for this purpose, it will be observed that the adding wheel shown is provided with but eight teeth instead of ten which is the usual number employed in the handling of whole numbers.

The associated sector and rack are piv- 105 oted on a shaft 16 which also carries the regular group of sectors and racks and these 110

associated elements are adapted to advance to the printing line, when released under the influence of springs 17, connecting the heel 17^a of the sector with a fixed portion 5 of the machine. The heel 17^a coacts with a heel 14^a on the rack through the medium of a spring 14^b, and the associated rack and sector are connected by the provision of a pin 14^c extending laterally from the 10 rack into a slot 14^d in the adjacent sector, as is common in the type of machines to which the present invention pertains, which lost motion connection is necessary to permit the required movement of the rack when 15 carrying, as set forth in the Hopkins Patent No. 1,039,130. The movement of the designating sector rack is limited by the provision of an inturned heel 18 which will be stopped by an elevated stop 19 in the trans- 20 versely movable carriage 11, which moves from right to left and from order to order with the regular operation of the machine. Since the fractions or designating symbols will be set up after the whole numbers have 25 been introduced into the stop carriage, the right hand row of stops in the stop carriage will also constitute the row which co-acts with the designating column mechanism, and this row will register with tappets 20 30 on the rear ends of key levers 21 (Fig. 6) which make suitable connection with keys, not shown, occupying a convenient or appropriate position on the keyboard in association with the usual keys which control 35 the introduction of whole numbers as shown in Hopkins Patent No. 1,039,130. A depression of one of the symbol or fractional keys will lift a tappet and raise the intended stop in a manner identical with that observed in the setting of stops by keys 40 representing whole numbers.

It is evident, however, that in introducing a fraction or designating symbol, it is necessary to block the further movement of the 45 stop carriage from order to order, which attends the pressing of a regular numeral key, since the fraction or symbol constitutes the ultimate right hand constituent of the item being introduced, and mechanism for blocking such carriage movement will now be described.

In preparation for the introduction of a fraction or symbol, a designating column key 22 is depressed, which key is mounted upon an arm 23 rigid on a transverse rock shaft 24, which also carries an arm 25 pivotally connected with a link 26, the rear end of which is slidably mounted within a fixed bracket plate 27 extending cross wise 55 of the machine near the rear side thereof. The depression of the designating column key 22 causes a forward sliding movement of the link 26, which is provided on its upper edge near its rear end with a beveled cam elevation 28 which is positioned to en-

gage a pin 29 on a latch finger 30 hooked at its forward end to engage a notch 31 near the rear upper edge of the rack bar 14 immediately above the heel thereof.

As shown in Fig. 5, the latch finger 30 70 constitutes part of a U-shaped bail 32 which terminates at its opposite end in a finger 33, the bail as a whole being pivoted on a rod 34, the ends of which are entered through and held within the arms 35 of a 75 fixed bracket 36 secured to the bracket plate 27. A spring 37 secured to a stud 38 at its upper end and to the cross connecting portion of the bail at its lower end serves to exert a downward thrust on the forward 80 end of the bail and to hold the latch finger normally in engagement with the notch 31 on the rack bar until lifted by the cam face 28 on the link 26. The bail finger 33 carries an outwardly projecting stud 39 which 85 is adapted to be lifted either by the actuation of the subtraction release mechanism, of Fig. 8, or by the total release mechanism of Fig. 9 in a manner presently to be described, so that the latch for the designating column rack will be released when any one of the three mechanisms mentioned is set in operation.

The forward movement of the link 26 also actuates means for blocking the escape- 95 ment of the stop carriage, which means will now be described. The rear end of the link 26 abuts against an arm 40 mounted at the upper end of a vertical rock shaft 41 journaled at its upper end through the bracket 100 plate 27 and at its lower end through a lower bracket 27^a (see Fig. 1), and the rock shaft near its lower end carries a laterally projecting lower arm 42 provided with a depending pin 43 which engages the heel 105 of a pawl 44 freely pivoted upon the rock shaft. The heel of the pawl has secured thereto a spring 45 which holds the pawl under tension against the pin 43, so that as the latter is withdrawn, the pawl will follow the pin and cause the nose 46 of the pawl to advance into the path of movement of a ratchet plate 47 secured to the rear side of the transversely movable stop carriage, as indicated in Figs. 3 and 7. Thus 110 when the designating column key 22 is depressed, the designating column rack and sector will be unlocked and free to advance to the limit of movement unless arrested by a subsequently positioned stop in the stop 115 carriage and at the same time the escape- 120 ment of the stop carriage will be arrested by the projection of the pawl.

When the pawl has been moved to arresting position, it will be locked by the mech- 125 anism shown in Fig. 3, which includes a latch lever 48 pivoted on a stud 49 in close proximity to the pawl 44, which latch lever is provided with a depending tongue 50 adapted to engage with a notch 51 formed 130

in the heel of the pawl when the latter has been moved to position to arrest the escapement of the carriage. The latch lever is acted upon by a spring 52, so that as soon as the pawl has been actuated, the tongue 50 will spring into position and prevent release of the pawl.

The pawl, however, is provided with a finger 53 which occupies a position within the line of movement of a rear plate 54 secured to the carriage, so that as the carriage is restored by the means regularly employed in a machine of this character, the plate will be brought into contact with the latch finger, and the latch released from engagement with the pawl upon which the superior tension of a spring 55 secured to the link 26 and exerting tension towards the rear, will cause the latter to move rearwardly against the combined tension of the pawl spring 45 and a similar spring 56, which engages the arm 40 and holds the same in close abutment to the rear end of the link 26.

The subtraction release mechanism of Fig. 8 comprises a link 57 which moves forward (to the right in Fig. 8) as the subtraction key is depressed and carries with it the depending bent arm 58 provided with a cam end 59 which bears against the laterally projecting pin 39 on the bail arm 33, which movement results in a lifting of the latch end of the bail and a release of the rack 14.

When either the total or sub-total key is depressed, a link 60 (Fig. 9) will be moved to the rear, which link carries at its rear end a plate 61 provided with a cam extension 62 bearing against the forward side of the same pin 39, so that movement of these parts, like a movement of the subtraction mechanism, will effect a lifting of the active end of the bail and a release of the rack.

Where the designating column mechanism is used for the purpose of imprinting symbols rather than fractions, the arms 58 and 61 are disconnected by removing the screws 63 and 64 respectively, and the designating column and adding wheel is also removed, so that a release of the rack in these circumstances can be effected only by the depression of the designating column key, so that the type sector alone will function to imprint the desired symbol.

In operation, when it is desired to utilize the mechanism herein described for the purpose of imprinting and accumulating fractions, the machine will be operated in the usual manner to set up stops representing whole numbers in an item after which the designating column key will be depressed to release the corresponding rack and printing sector and to lock the carriage against escapement. Thereafter, the fractional key is depressed to set up a stop in that line of stops in the carriage which, for the time being, represents the intended fraction after

which, upon a pull of the operating handle, the several type sectors and associated racks, including the designating column rack will advance until arrested by the stops and the item will be printed in the usual manner. Upon release of the handle the adding wheels will be thrown into mesh with the corresponding racks and the item accumulated in the usual manner. Of course, the usual carrying mechanism in association with the adding wheels and racks is utilized to carry from a lower to a higher order, and the same mechanism is of necessity provided for carrying from fractions into whole numbers.

The return of the carriage to its right hand position will automatically release the escapement latch, so that in setting up a new item, the carriage will be free to escape until again locked by the action of the designating column key.

The device as a whole is one which is adapted for use in association with and as a part of the regulation adding machine without any substantial change or modification in the construction and arrangement of the machine as a whole and without adding in any noticeable degree to the bulkiness of the machine.

I claim:

1. In designating column mechanism for adding machines in combination with a printing device and associated rack and an adding wheel, key controlled means for unlatching the printing device and rack, a stop carriage relatively movable with respect to the rack, and means for preventing relative movement of said parts as incidental to the introduction of an item into the designating column, and means associated with the carriage for releasing said carriage arresting means during the restoration of the carriage to normal position, substantially as described.

2. In designating column mechanism for adding machines in combination with associated printing mechanism, a rack, and an adding wheel, a stop carriage transversely movable with respect to said members and provided with stops adapted to be set to limit the movement of the printing mechanism and rack when released, key controlled mechanism adapted, when actuated, to unlatch the printing mechanism and rack and lock the carriage against escapement during the introduction of an item into the designating column, and means associated with the carriage for releasing said carriage arresting means during the restoration of the carriage to normal position, substantially as described.

3. In designating column mechanism for adding machines the combination of a type sector, an associated rack, an adding wheel, a latch for normally holding the rack and type sector against movement, a transversely

- movable stop carriage provided with stops adapted to limit movement of the type sector and rack when unlatched, a carriage escapement lock, a designating column key 5 adapted when operated to release the latch and set the lock to prevent further escape-
ment of the carriage, and means carried by the carriage and adapted on a restoring movement of the carriage to restore the lock 10 to non-locking position, and total mechanism adapted, when actuated, to effect an unlatching movement of the latch, substan-
tially as described.
4. In designating column mechanism for 15 adding machines the combination of a pivoted type sector, an associated pivoted rack movable therewith, a bail having a latch arm normally in latching engagement with the rack, a lifting arm provided with an outstanding pin, a designating column 20 key, a link connected with said key, and adapted when moved to lift said bail and disengage said latch, a transversely mov-
able stop carriage provided with stops in co-acting relation with said rack, an escape-
ment ratchet on said rack, a pawl adapted to engage said ratchet, and connections for said pawl adapted to engage the key controlled link for simultaneously releasing said rack 25 and locking said escapement, and total de-
vices in engagement with the outstanding pin on said lifting arm and adapted when actuated to lift said bail and effect release of said latch, substantially as described.

HARRY LANDSIEDEL.
